MACHINE FOR MAKING LONGITUDINALLY
CURRED REINFORCED SHANK STIFF-
ENERS

William H. Nickerson, Newton, Mass.

Application September 1, 1933. Serial No. 687,805

6 Claims. (Cl. 12—60)

This invention relates to the manufacture of a shoe shank stiffener composed of a non-metallic flexible body portion, usually of leatherboard, and a longitudinally extending relatively stiff and ⁵ silent metal reenforce provided with prongs which penetrate and are clinched on the body portion.

The object of the invention is to provide a shank stiffener machine including uniting and ¹⁰ bending mechanism adapted by one operation to unite the stiffener parts by inserting the prongs of the reenforce in the body portion and clinching said prongs, and at the same time bending the assembled body portion and reenforce, to impart a ¹⁵ desirable longitudinal curvature to the stiffener, said curvature being maintained by the clinching of the prongs. The uniting and bending mechanism of the present invention constitutes a part of a machine which includes the mechanism for ²⁰ forming prongs, and, if desired, hollow ribs on a strip of reinforcing metal of indeterminate length, in such manner that the strip may be severed by the uniting and bending mechanism into lengths each constituting a complete reen- ²⁵ force which is united to a body portion applied by hand, or otherwise, to the uniting and bending mechanism.

Of the accompanying drawings forming a part of this specification,—

³⁰ Figure 1 is a longitudinal sectional view showing a shank stiffener machine which includes the uniting and bending mechanism of the present invention.

Figure 2 is a section on line 2—2 of Figure 1.

³⁵ Figure 3 is a section on line 3—3 of Figure 1.

Figure 4 shows in perspective a strip of re-enforcing material prepared for the uniting and bending mechanism.

Figure 5 shows in perspective a metal reenforce ⁴⁰ as severed from the strip by the uniting and bending mechanism.

Figure 6 is a top plan view showing the lower die of the uniting and bending mechanism, the upper die being removed.

⁴⁵ Figure 7 is a section on line 7—7 of Figure 6 showing the upper die depressed.

Figure 8 is a section on line 8—8 of Figure 1.

Figure 9 is a section on line 9—9 of Figure 7.

Figure 10 is a view similar to portions of Figure ⁵⁰ 9 showing the operation of ejecting a completed stiffener.

Figure 11 is a perspective view of the completed stiffener.

The same reference characters indicate the ⁵⁵ same parts in all of the figures.

The machine which includes the uniting and bending mechanism in which the invention is embodied, is shown at the right of the line *x* *x* in Figure 1. The mechanism shown at the left of said line is a strip treating mechanism adapted to impart to a metal strip 12 of indeterminate length, the features shown in perspective by Figure 4, said features including prongs 13 bent downwardly from the strip at spaced apart points, and intermediate portions 14 adapted to be severed at 15, as hereinafter described, by elements of the uniting and bending mechanism to produce the incomplete metal reenforce 151, shown by Figure 5. Said features may include also spaced apart longitudinal grooves each forming a hollow rib 16 on the metal reenforce adapted to be pressed into the body portion 24, described later.

The strip treating mechanism may be substantially similar to that shown by my Patent No. ⁷⁵ 1,593,349, dated July 20, 1926, and is organized as described by that patent to form the prongs 13, and the intermediate portions 14, but not to sever said portions at 15, this function being performed by the uniting and bending mechanism.

The strip treating mechanism may include a lower female grooving die 160 fixed to a base 17, an upper male grooving die 18 fixed to a vertically movable carrier 19, and prong forming means shown conventionally at 20.

⁸⁰ The machine is provided with means for longitudinally feeding the strip 12 step by step, as described by my above mentioned patent, said means including feed rolls 61.

The uniting and bending mechanism comprises a lower bending and clinching die 22 having a longitudinally concave pressing and prong clinching face 23, and means for positioning on said face the non-metallic body portion 24 of a two-part shank stiffener. Said means is preferably embodied in stops 25 fixed to the lower die, and projecting upward and spaced from one side thereof, as shown by Figures 8, 9 and 10, said stops abutting one longitudinal edge of the body portion 24, and correctly positioning it when said body portion is placed on the lower die.

⁹⁰ The lower die 22 is suitably fixed to the base 17, shown by Figure 1.

26 designates an upper bending die having a convex pressing face 27, and secured to the carrier ¹⁰⁵ 19 whereby it may be moved vertically toward and from the lower die.

The upper die 26 is provided with a shearing member 29 adapted to cooperate with a shearing member 30 on a block 31 fixed to the lower die,

110

the member 30 projecting over one end of the lower die, as shown by Figure 7.

When the upper die descends, the reenforce, in the condition shown by Figure 5, is severed from the strip, pressed against the body portion 24, and bent therewith until the stiffener is curved as shown by Figure 7. At the same time the prongs 13 are clinched against the face 23 of the lower die, as shown by Figure 7, so that they maintain the curvature.

10 The now completed stiffener in the condition shown by Figure 11 may be ejected by a knocker 33 oscillated by any suitable means, and arranged to strike the edge of the body portion 24 abutting the stops 25, and displace the stiffener, as indicated by Figure 10.

I claim:

1. A machine for making longitudinally curved reenforced shank stiffeners, including uniting and bending mechanism comprising a lower bending die having a longitudinally concave pressing and clinching face, means for positioning the non-metallic body portion of a shank stiffener thereon, an upper bending die having a convex pressing face, and means associated with said dies for severing, from a previously pronged metal strip, a reenforce having prongs at its opposite end portions, said dies being relatively movable to cause the upper die to force the reenforce prongs into the body portion, bend the reenforce and body portion and thereby impart a longitudinal curvature to the stiffener, and clinch the prongs of the reenforce to maintain said curvature.

2. A shank stiffener machine as specified by claim 1, said severing means including a shearing member carried by the upper die, and a co-operating shearing member fixed to the lower die, and projecting over one end thereof.

3. A shank stiffener machine as specified by claim 1, the means for positioning a shank body portion of the lower die being embodied in fixed stops projecting upwardly from the lower die, and arranged to abut only one edge of said body

45

portion, and permit the positioning of the body portion on the lower die by an edgewise movement in one direction, and its removal by an edgewise movement in the opposite direction.

4. A shank stiffener machine as specified by 80 claim 1, the means for positioning a shank body portion on the lower die being embodied in fixed stops projecting upwardly from the lower die and arranged to abut only one edge of said body portion, and permit the positioning of the body portion on the lower die by an edgewise movement in one direction, and its removal by an edgewise movement in the opposite direction, the machine comprising also a knocker movable to cause the removal of the stiffener from the lower die.

5. A machine for making longitudinally curved reenforced shank stiffeners, comprising pronging mechanism having means for forming prongs at spaced apart intervals on a flat metal strip, and means for feeding said strip; uniting and bending mechanism comprising a lower bending die having a longitudinally concave pressing and clinching face, means for positioning the non-metallic body portion of a two part stiffener 100 thereon, an upper bending die having a convex pressing face, said dies being in the path in which said strip is fed from the pronging mechanism, and means associated with said dies for severing from said strip a reenforce having prongs at its 105 opposite end portions, said dies being relatively movable to cause the severing of said reenforce from the strip, force the reenforce prongs into the body portion, bend the reenforce and the body portion, and thereby impart a longitudinal 110 curvature to the stiffener, and clinch the prongs of the reenforce to maintain said curvature.

6. A shank stiffener machine as specified by 115 claim 5, said pronging mechanism having means for forming in said strip longitudinal grooves alternating with the prongs, each groove providing, in a reenforce severed from the strip, a longitudinal stiffening rib.
